UNITED STATES PATENT OFFICE

WILLIAM A. HEIDE, OF DETROIT, MICHIGAN

CARBURETOR

Application filed April 19, 1923. Serial No. 633,210.

This invention relates to carburetors.

It is an object of the invention to provide a carburetor having novel controlling means whereby the engine can be primed readily for the purpose of starting it and whereby the flow of air and fuel can be controlled effectively under various circumstances.

Another object is to provide novel means for controlling the flow of air past the fuel nozzle, for reducing the inflow of air and for otherwise controlling the flow of air and gas through the carburetor.

With the foregoing and other objects in view which will appear as the description proceeds, the invention consists of certain novel details of construction and combinations of parts which will be hereinafter more fully described and pointed out in the claim, it being understood that changes may be made in the construction and arrangement of the parts without departing from the spirit of the invention as shown.

In the accompanying drawings the preferred forms of the invention have been shown.

In said drawings,

Figure 1 is a plan view of the improved carburetor, portions being shown in section.

Figure 2 is a vertical median section on the line 2—2 of Figure 1, portions being shown in elevation.

Figure 3 is a plan view of the air choke valve.

Figure 4 is a horizontal section on the lines 35 4—4 of Figure 2.

Figure 5 is a fragmental side elevation illustrating the operating means of the air choke valve and corresponding parts.

Figure 6 is a vertical section of a modified form of carburetor, portions being shown in elevation.

In carrying out the invention, referring particularly to Figures 1 to 5, inclusive, there is provided a fuel receptacle or cup 1 having secured upon its rim a removable cover 2, which has seated thereon and extending diametrically across the same, the horizontal air suction pipe 3, provided at its discharge end with suitable means 4 for attaching it to the intake manifold or conduit of an internal

combustion engine. The receptacle 1 is provided at a suitable point thereof above the fuel level with an air vent aperture 5, and the pipe 3 can be secured upon the cover by means of one or more screws 6 engaged upwardly through the cover and threadedly engaging the pipe.

A fuel cup 7 is engaged upwardly through a central opening in the cover 2 and is threaded upwardly through the bottom of the pipe 3 intermediate the ends thereof, said cup having an outstanding flange 7' bearing upwardly against the cover 2. A fuel nozzle or tube 8 depends from the bottom of the cup 7 centrally thereof to dip in the fuel within the receptacle 1, and the flow of fuel from the receptacle into the lower end of the tube 8 is controlled by means of a valve 10 seatable against and cooperable with the lower end of the tube. The valve 10 is carried by and extends upwardly from the intermediate portion of a lever 12 within the receptacle 1. This lever has one end pivoted to a hanger 13 attached to the cover 2 and disposed adjacent to one side of the receptacle. The other free end of the lever threadedly engages the lower threaded terminal of a vertical stem or spindle 15 adapted to be rotated in a lug 11 mounted upon the cover 2 at one side of the pipe 3. The stem 15 can be supported in the lug 11 by any suitable means. For example a screw 16 or its equivalent can be used for engaging the stem and the lug 11 can be split as at 17. This split portion has a screw 18 whereby it can be contracted about the stem 15 so as to grip the same. Obviously by loosening the stem and rotating it the threaded end thereof will work in lever 12 and move the valve 10 toward or from its seat. Thus the flow of fuel through the tube 8 and into the cup 7 can be regulated. See my co-pending application Serial No. 379,541, filed May 7, 1920.

An air suction member 9 is fitted within the pipe 3, and the rim of the fuel cup 7 is threaded upwardly into said member 9, said member providing a constricted portion of the air suction passage with which the mouth of the fuel cup 7 communicates.

The lug 11 is provided near one end with a

fuel inlet passage 19, and a fuel supply pipe 19' is connected to the lug in communication with the passage 19, and with the receptacle 1, to deliver the fuel into said receptacle.

5 In order to maintain the fuel level normal within the receptacle 1, a float 20 is provided therein, having an opening 22 through which the fuel tube 8 extends loosely. This float carries the usual valve adapted to engage the 10 valve seat at the end of the fuel inlet passage 19 and thus control the passage of fuel through the inlet.

A throttle valve 26 of the butterfly type is mounted within the discharge end of the 15 pipe 3 and is carried by a vertical spindle 27 journaled through said pipe, said spindle having an operating arm 28 at its upper end adapted to be controlled manually in any suitable manner, whereby the engine can be 20 throttled as usual. The throttle valve 26 controls the air suction within the pipe 3, to thereby control the amount of fuel used.

As a means for supplying a priming charge 25 of fuel to the air flowing from the pipe 3, when the engine is started, a tube 29 is provided, one end extending within and communicating with the lower portion of the receptacle 1, said tube extending through one side of the receptacle, and having its other 30 end soldered or otherwise secured to one side of the pipe 3 adjacent to the discharge end thereof and adjacent to or slightly in advance of the throttle valve. The adjacent portions of the pipe 3 and tube 29 are provided with an oblique aperture 30 extending in the general direction of the flow of air through the pipe, and said aperture is located adjacent to and immediately in advance of the throttle valve, one edge or wing of said 40 valve being disposed immediately adjacent to or behind the aperture 30 when the valve is closed, and being cut away, as at 31, to provide a by-pass between said wing of the valve and side wall of the pipe 3 when the valve is closed. This allows a small current of air 45 to pass through the by-pass past the valve and aperture 30, the suction extending through the aperture 30 into the tube 29, whereby when the engine is started, with the 50 throttle valve 26 closed or near closed position, a priming charge of fuel will be sucked from the tube 29 into the manifold to start the engine easily.

The air choke and controlling valve 32 extends into the air choke member 9 from the receiving end thereof toward the mouth of the cup 7, with the free end of said valve swingable toward and away from the mouth of said cup. The valve 32 is pivoted, as at 33, within the member 9 diagonally opposite to the cup 7, said valve being pivoted between its ends, and its other end portion is swingable within a slot 34 with which the member 9 is provided, and a longitudinal slot 35 in 60 the top of the pipe 3, above the slot 34. The

valve 32 which normally extends downwardly at an angle to the cup 7, is provided with an elongated longitudinal opening or slot 36, normally closed by a leaf spring valve 37 bearing against the lower surface of the valve 32 and secured, as at 38, to the valve 32 adjacent to its free end. The valve 37 is held seated against the valve 32 by its spring tension, so as to ordinarily close the opening 36, but in case of a back fire in the engine, resulting in the reverse flow of air and gas through the pipe 3, the choke valve 32 being closed, will enable the compressed air and gas to escape through the opening 36, the valve 37 being sprung open downwardly away from the valve 32. The valve 37 and opening 36 can be eliminated if not wanted.

As a means for operating and controlling the choke valve 32, a forwardly extending arm 39 is disposed snugly within the opening or slot 35 and its rear end is mounted upon a rock shaft 40, it being secured thereto by means of a pin 41 or otherwise, and said rock shaft is journaled through upstanding flanges or bearings 42 with which the pipe 3 is provided at opposite sides of the opening 35. The forward portion of the arm 39 extends upwardly at an angle, as at 43, so that the upper terminal of the valve 32 can seat upwardly thereagainst, as seen in Figure 2. The inclined portion 43 is provided at the end of the arm 39 and side edges of the portion 43 with the depending aprons 44 and 45, respectively, to snugly fit the pipe 3 around the opening 35 for preventing leakage when the arm 39 is swung downwardly against the pipe 3. The upper terminal of the valve 32 is held yieldably against the portion 43 of the arm 29, and for this purpose, a stem 46 is slidable through said portion 43 and extends through an open slot 47 with which the upper terminal of the valve 32 is provided, said stem 46 having a head 48 at its lower end seating upwardly against the upper terminal of the valve 32. A coiled wire expansion spring 49 surrounds the stem 46 above the arm 39, and is confined between the portion 43 and an adjustable nut 50 threaded upon the stem. Said nut can be rotated for adjusting the tension of the spring 49 to thereby hold the upper terminal or arm of the valve 32 against the portion 43 with the desired tension. A stop screw 51 is threaded through the arm 39 between its pivoted end and portion 43 to limit the movement of the upper terminal of the valve 32 toward the arm 39, said stop screw 51 being held in any adjusted position by means of a lock nut 52 thereon. When the arm 39 is swung downwardly against the pipe 3, this will hold the valve 32 in inclined position so as to extend rearwardly and downwardly to the mouth of the cup 7, as seen in Figure 2, but the rear lower terminal of the valve 32 can swing upwardly, due to the air suction, which will 105 110 115 120 125

swing the upper terminal of the valve downwardly, pulling the stem 46 therewith to compress the spring 49, which resists such movement of the valve. When the arm 39 is swung upwardly, the stem 46 is moved yieldably with the arm, thereby pulling the upper terminal of the valve 32 with the arm 39 and swinging the lower active terminal of the valve 32 downwardly against the bottom of the member 9, to shut off the flow of air or choke the air suction passage, thereby reducing or restricting the flow of air into said passage.

The arm 39 is operated by means of a lever 53 secured upon one terminal of the rock shaft 40 by means of a set screw 54 or otherwise, and having an upwardly extending arm 55 to which a rod or link is connected for operation by a foot or hand lever or other operating member. The lever 53 has another arm 56 to which an adjusting screw 57 is threaded, said screw being held in any adjusted position by means of a lock nut 58 thereon. The lower end of the screw 57 bears upon a disk 59 seating upon the upper convolution of a coiled wire compression spring 60 having its lower convolution held upon the cover 2 by means of a suitable seat 61. The spring 60 in expanding will raise the arm 56 whereby to turn the shaft 40 for swinging the arm 39 downwardly, and by swinging the arm 55 rearwardly, this will raise the arm 39.

The flow of fuel into the pipe 29 is controlled by a valve 62 seatable against the inner end 63 of said pipe, as seen in Figure 4, the valve 62 preferably having a pin 64 extending into the pipe 29 for guiding the valve to its seat. The valve 62 is carried by a stem 65 that is pivoted to a radial arm 66 carried by a vertical rock shaft 67 mounted for rotation within the receptacle in any suitable manner, and extending up through the cover 2 thereof. A suitable spring 68 tends to swing the arm 66 toward the pipe 29 for seating the valve 62, and a lever 69 is secured upon the upper protruding terminal of the rock shaft, said lever having a split portion 70 embracing the shaft and carrying a clamping screw 71 for tightly securing the lever to the shaft. The lever has an outstanding arm 72 whereby it can be swung through the medium of a suitable operating device. The lever has an inwardly extending arm 73 projecting below the rock shaft 40 to be engaged by the downwardly extending arm 74 of the lever 53, whereby when the arm 55 is swung rearwardly to completely close the valve 32, the arm 74 in striking the arm 73 will swing the lever 69. This will swing the arm 66 away from the tube 29 to open the valve 62 so that the fuel can flow into said tube.

In operation, when the lever 53 is released, it will be swung under the influence of the spring 60 to swing the arm 39 downwardly against the pipe 3, and the choke valve 32

will therefore swing partially open, as seen in Figure 2, while the lever 69 is released to permit the valve 62 to close under the influence of the spring 68. This prevents the flow of fuel through the tube 29 excepting when the valve 32 is closed. It will be noted that the valve 32 in extending at an angle to the mouth of the cup 7, will direct all of the air across the mouth of said cup, thereby creating an air suction and eddies within the cup to effectively atomize and mix the fuel and air, the fuel being sucked upwardly through the tube or nozzle 8 into the cup 7 and pipe 3 and passing off with the air. As the suction increases, to increase the volume of air flowing through the pipe 3, the lower free end of the valve 32 can swing upwardly away from the cup 7, but it will be noted that in doing so, the spring 49 is compressed, thereby resulting in the air being constrained to pass closely over the cup 7. The normal position of the valve 32 can be controlled by adjusting the stop screw 51. Thus, with the arm 39 in normal position, by adjusting the screw 51 downwardly, this will raise the lower end of the valve 32. The engine is throttled as usual by means of a throttle valve 26.

In starting the engine, the arm 55 of the lever 53 is swung forwardly, whereby to raise the arm 39 and yieldably swing the upper terminal of the valve 32 upwardly, to close the said valve and bring the lower free end thereof against the bottom of the air choke member 9, thereby shutting off or restricting the flow of air through the pipe 3 over the cup 7. Furthermore, the movement of the lever 53 will result in the arm 74 swinging the arm 73 to open the valve 62 whereby the fuel can now flow from the reservoir 1 through the tube 29 and aperture 30 for enriching the mixture to easily start the engine, especially when the throttle valve is closed to increase the suction through the aperture 30 and tube 29. At any position of the valve 32, it can open against the tension of the spring 49, when the tension of said spring is overcome, but when the arm 39 is raised, the spring 49 will result in the valve 32 being held closed with considerable tension. Should there be a back fire of the engine, resulting in the reverse flow of air and gas through the pipe 3, this will be permitted due to the fact that that air and gas can flow through the opening 36 of the valve 32, the auxiliary spring valve 37 being sprung open downwardly. In this connection, it is to be noted that the upper free terminal of the valve 37 will spring downwardly first, so that the air and gas will flow through the upper portion of the opening 36, being directed upwardly away from the cup 7 by the valve 32, so that the reverse flow of air and gas through the pipe 3 will not result in an appreciable amount of fuel being drawn

from the cup 7 and wasted. The valve 32 although it causes the inflowing air to pass immediately across the mouth of the cup 7, will deflect the outflowing air away from said cup, with the foregoing advantages derived by such function of the valve 32.

The modification illustrated in Figure 6 uses the same arrangement of valve 10, lever 12, and their operating means, as already described with reference to the structure shown in Figures 1 to 5 inclusive. In this form, however, the air suction pipe 3^a extends vertically through the receptacle or reservoir 1^a having the cover 2^a mounted upon said pipe, the bottom of the receptacle being threadedly or otherwise engaged upon the lower terminal of the pipe 3^a to bring the rim of the receptacle against the cover, a suitable packing 3^x being provided between the bottom of the receptacle and pipe 3^a. The pipe 3^a has a laterally extending branch 3^y above the cover 2^a in which an air choke member 9^a is disposed, similar to the member 9 above described, and having assembled therewith, the fuel cup 7 and a simple air choke valve 32' held closed over the cup 7 by a spring 49 between the branch 3^y and nut 50 on rod 46. This valve 32' normally closes the branch 3^y when the suction is low and opens as the suction increases. A second depending fuel tube 8^a is provided, the same having its upper end attached to one side of the pipe 3^a underneath the cover 2^a and communicating with a fuel cup or recess 7^a with which the air choke member 9^a within the pipe 3^a below the branch 3^y is provided. Separate valves 10' and 10'' are provided for the tubes 8 and 8^a, and can be controlled in any suitable manner. The float 20^a surrounds the pipe 3^a within the receptacle, and is hinged, as at 21^a, to the cover which has a lug 11^a above the hinged portion of the float provided with the fuel inlet port 19^c and a valve seat 19^y at the lower end of the port 19^x against which the valve 22^x is seatable upwardly. Said valve is connected to the hinge member 25^a upon the float 20^a. The fuel supply tube 19^c is connected to an attaching member secured on the lug 11^a and having a conical ground fit therewith. A priming fuel tube 29^a extends upwardly through the cover along the pipe 3^a, and the flow of the fuel into the lower end of said tube is controlled by a valve 62 and operating device therefor similar to the corresponding parts above described. The upper end of the tube 29^a opens into the pipe 3^a, as at 30^a, immediately above the throttle valve 26 mounted within the upper portion of the pipe 3^a above the branch 27. The shaft 67 and spring 68 are carried by a bracket 67' attached to pipe 3^a.

What is claimed is:

A carburetor including a fuel receptacle, a cover thereon, a suction pipe extending across the receptacle and downwardly through the

cover and the bottom of the receptacle, said suction pipe constituting means for holding the cover assembled with the receptacle, an intake choke member within the suction pipe, a fuel tube in the receptacle, a screw-threaded enlargement at one end of the tube recessed to provide a cup opening downwardly into the tube and upwardly into the choke member, said enlargement being in threaded engagement with the top of the receptacle, the suction pipe, and the choke member for holding them assembled and for supporting the fuel tube in the receptacle, a valve pivotally mounted in the choke member, one end portion of the valve being adapted to extend over the cup, and means for actuating the valve.

In testimony that I claim the foregoing as my own, I have hereto affixed my signature.

WILLIAM A. HEIDE.
